UNITED STATES PATENT OFFICE.

JOSEPH SIMPSON, OF COLUMBUS, OHIO.

LAMP-BRACKET AND MATCH-BOX COMBINED.

SPECIFICATION forming part of Letters Patent No. 268,952, dated December 12, 1882.

Application filed March 15, 1882. (No model.)

To all whom it may concern:

Be it known that I, JOSEPH SIMPSON, of Columbus, in the county of Franklin, and in the State of Ohio, have invented certain new and useful Improvements in Lamp-Brackets; and I do hereby declare that the following is a full, clear, and exact description thereof, reference being had to the accompanying drawings, and to the letters of reference marked thereon, making a part of this specification.

This invention has for its object to provide an improved bracket, which may be employed to support a lamp, a suspended flower-basket, or other article, as more fully hereinafter specified. This object I attain by the means illustrated in the accompanying drawings, in which—

Figure 1 represents a side elevation of my improved bracket complete, with the lamp-holding ring or basket; Fig. 2, a vertical sectional view of the bracket-support and match-box; and Fig. 3, a perspective view of a flower-pot holder or ring detached, which is adapted to be employed in connection with my improved bracket.

The letter A indicates my improved bracket, which is provided at one end with a pintle, B, adapted to set in suitable bearings, C, in the support D, which may be attached to a wall by means of screws or otherwise. The free end of the bracket is curved upward, as shown, forming a hook to which the ring or basket D' may be attached, the bracket being provided with lugs F on each side to support the ring or basket.

The letter G indicates a hook formed on the bracket, from which may be suspended a flower-basket or other article.

The bracket-support is made of cast metal,

with a receptacle, H, for matches, and with 40 bearings for the pintle of the bracket.

It will be perceived that the bracket as thus constructed is adapted to hold a ring or basket for a lamp, or a support for a flower-pot or other article, and that it may also be employed 45 without such ring or support to support various ornamental articles—such as flower-baskets, bird cages, and the like.

The bracket-support is attached to a wall or other article by means of screws or other 50 fastening devices, the face of the wall forming one side of the match-receptacle.

It is evident that the bracket may be made of any configuration or design without departing from the spirit of my invention.

The ring or basket is provided with a lug, L, which is formed with a suitable aperture in order that it may be attached to the hooked or curved end of the bracket, as indicated in Fig. 1 of the drawings.

Having thus described my invention, what I claim, and desire to secure by Letters Patent, is—

In combination with the support D, provided with pintle-bearings C C C, constructed as described, the bracket A, having a pintle, B, adapted to set in said pintle-bearings, and provided with hooks at the ends, and with lugs at each side, adapted to support the rings and baskets, substantially as herein specified. 65 70

In testimony whereof I affix my signature, in presence of two witnesses, this 10th day of March, 1882.

JOSEPH SIMPSON.

Witnesses:

GEO. S. ARTZ,

DAVID C. WELLING.
